CORING DEVICE FOR BALED GOODS

Richard T. McAndrew, Braintree, Mass., assignor to United States Testing Company, Incorporated, Hoboken, N. J., a corporation of New York

Application February 7, 1951, Serial No. 209,840

5 Claims. (Cl. 73—425.2)

1

This invention relates to coring devices used for obtaining samples of baled goods, and in particular is directed to improvements in the structure of such devices whereby the size of the sample removed is drastically reduced thereby to provide great economies in the expense of sampling.

It has been the practice heretofore in obtaining samples of baled goods, such as wool, to employ a motor driven coring device, which penetrates the bale to a substantial depth thereby to obtain a large core (diameter of approximately 2-3") of the goods. In the case of wool the core is removed from the coring tube and sent to the laboratory for appropriate analytical procedures in order to ascertain its composition. Several major problems are presented in carrying out such coring operations. One, is the fact that the coring tool has a tendency to jam with resultant difficulty in obtaining an adequately representative sample of the goods in the bale. Another, is that the devices heretofore used have coring tubes of very large diameter, resulting in the removal of large cores of the wool with consequent very substantial losses of the wool removed, and also loss of time entailed in processing the wool in the laboratory in carrying out the analysis thereof.

This invention is directed to improvements in the structure of coring devices, particularly the cutting tube thereof, whereby it now becomes possible rapidly to obtain a small representative sample of the wool contained in a bale; and, accordingly, it is one of the primary objects of this invention to provide the art with a coring device that removes a substantially smaller sample than has heretofore been possible to obtain.

Another object of the invention is to provide a coring device that removes a substantially smaller sample than has been required heretofore, and thereby to effectuate drastic economies in time consumed in the laboratory in carrying out the analyses of the samples, as well as greatly to minimize the loss of the wool, per se, required to carry out such analyses.

In its fundamental aspects the primary object of this invention is achieved by a device comprising a coring tube of relatively small cross section provided with a cutting edge at one end thereof, the internal diameter of which cutting edge is slightly smaller than that of the body of said tube thereby allowing the core, as it passes the cutting edge and moves upwardly in the tube, to expand sufficiently to overcome the jamming heretofore encountered.

Another feature of this invention is achieved

2

by this novel coring device which comprises means constituting part of the structure whereby the sample of the wool, as it is removed from the bale, may conveniently be collected in a receptacle therefor carried by the coring device. Accordingly, it is another of the primary objects of this invention to provide a coring device which is adapted to receive and collect the cores removed from the bale.

10 That primary objective is achieved by means of a coring device having a coring tube, provided with the cutting edge described above, that is operatively connected to a communicating housing for a removable receptacle adapted to receive the cores taken from the bale being sampled.

The device of this invention may be driven by an appropriate power element, such as has heretofore been used for driving the coring tubes. In view of the drastic reduction in the diameter of the core being removed and the ease of its upward movement in the coring tube of this invention, the whole device can readily be operated by a manually holdable power element to which the coring structure is connected.

15 The foregoing objects and advantages as well as other objects and advantages of this invention will become more fully understood from the detailed description thereof, taken in connection with the accompanying drawings wherein:

Fig. 1 is an exploded view of an embodiment of this invention, the power element being partially shown, and in dotted outline.

20 Fig. 2 is a longitudinal view, partly in cross section, showing the structure of Fig. 1 in assembled relation.

Fig. 3 is a view of the cutting edge of the tool shown in Fig. 2, taken on the line 3—3 thereof.

25 Fig. 4 is a view partially broken away, of the sample collecting receptacle (after removal from the housing therefor constituting part of the coring device) showing it filled with the collected sample.

Fig. 5 is a view, partially in section, showing the means of affixing the coring tube to the sample collecting housing.

30 Fig. 6 is a view partially in section, showing another form of coring tube, as for example a tapered tube, the same being assembled with the cutter and other members as shown in Figs. 1, 2 and 5.

35 Referring more particularly to the drawings, the numeral 10 designates a coring tube of uniform diameter, 12 the sample collecting housing or reservoir, and 14 the power element that drives the aforesaid combination of coring tube and

housing. The coring tube 10 is made of steel or any other appropriate material and carries, at its lower end 18, a removable cutting unit or member 20. As shown, the cutting unit 20 comprises a small cylindrical or tubular body 22 having a tapered shank 24, a shoulder 26, and a circular cutting tip or blade 30, welded to the body 22, as at 32. The cutting edge 34 of 30 may be of any appropriate configuration. The shank 24 tapers upwardly from the shoulder 26 so that it may be inserted and held frictionally and snugly engaged within the cooperatively flared portion 36 within the lower end of the coring tube, the bottom edge 38 of which tube abuts the shoulder 26.

The housing 12 comprises a cylindrically shaped main body member 40, and a cover 42. Body member 40 and the cover 42 are provided with means, respectively, to engage the coring tube 12 and the power element 14 so that rotation of 14 drives the coring tube. Housing 12 has a base 44 provided with an axially disposed orifice 46 to receive and engage the upper end of the coring tube. The cover 42 is provided with means to engage the drive shaft of 14. The cover 42 is secured to the body member 40, by means of the cooperatively disposed pins or studs 48 to engage the bayonet slots 50 in the housing.

As shown in Figs. 2 and 5, the engagement of the coring tube with the body member 40 is effected by means of bushing 56, extending through 46, and having internal threads 58 which receive the external threads 60 on the upper end of the coring tube. The cover 42 has an axially disposed bushing 62 that engages the drive shaft 64 of the power element.

An inverted can or receptacle 66 is positioned in the housing 12 so that the open end 68 thereof is in direct communication with the coring tube. The receptacle 66 is secured against movement by the pressure of bushing 62 against the base 70 of the receptacle while the open end 68 of the receptacle presses against the resilient floor member 72. The floor 72 may be made of a base of sponge rubber as at 74 and a top layer of sheet rubber as at 76. In carrying out a coring of a bale with the device, the operator holds the structure by any convenient handle (not shown in detail) affixed to the power element 14 and proceeds to "drill" or "core" the bale. As the cutting unit penetrates the bale, the core ascends the tube and enters the receptacle 66. The internal diameter of the cutting unit 20 is less than the internal diameter of the tube 10, thus permitting the core easily to move upward in tube 10 without jamming. In this way it is possible to collect a plurality of cores from a bale which are deposited in the receptacle. When the desired number of cores of wool or other material is collected, the cover 42 is disengaged from the body member 40, the receptacle 66 with its accumulation of cores is removed, and the receptacle then covered with its closure 78. The receptacle containing the sample of the material 80, as shown in Fig. 4, is then sent to the laboratory for analysis.

The objects and advantages of this invention may also be achieved by a structure in which a tapered coring tube 90, shown in Fig. 6, is used. Tube 90 is affixed to the housing 12 in the same way as is tube 10. Tube 90 is internally flared at its lower end 92 so as to engage the upwardly tapered shank of the cutting unit shown in Figs. 1, 2 and 3.

It will be understood that the ease of ascent of the core in the tube is achieved by the provision of a structure, as described for example above, in

which the internal diameter of the cutting unit is slightly less than the internal diameter of the tube.

Thus, in the embodiments described the coring tube 10 is made of stainless steel having an outside diameter of $\frac{1}{8}$ inch, and an inside diameter of one-half ($\frac{1}{2}$) inch. The inside diameter of the cutting unit 20 is 0.466 inch. The core thus can expand as it passes from the cutting unit into the tube with consequent release of pressure that otherwise causes the sample to jam, especially when the core is of the markedly reduced diameter that can be obtained with this new device. The markedly reduced diameter of the novel coring device of this invention over the larger diameters of the coring tubes heretofore used provides for drastic savings in the amount of wool removed from a bale being sampled, and results in sharp economies in the cost of analyzing the cores sent to the laboratory.

It will also be understood that a removable cutting unit may be employed in this device which comprises a removable circular cutting tip that is held in operative engagement by a removable blade or tip-holding member that is engaged by the lower or forward end of the coring tube.

It will be understood that the foregoing description of the invention and the embodiment shown is merely illustrative of the principles thereof, and accordingly the appended claims are to be construed as defining the invention within the whole spirit and scope thereof.

I claim:

1. In a coring device of the class described, a tube, a removable cutting unit engaged by the forward end of the tube, said cutting unit comprising a shank engageable within said tube, a body portion and a circular cutter carried by said body portion, the internal diameter of the tube being slightly larger than the internal diameter of said cutting unit, and a core collecting housing communicating with the rear end of said tube, said housing comprising a main body member of substantially greater diameter than the aforesaid tube and a removable cover member, said cover member having means for engaging the drive shaft of a motor.

2. In a coring device in the class described, a forwardly tapering tube, a circular cutter at the forward end of the tube, the internal diameter of the cutter being less than the internal diameter of the said tube, and a core collecting housing of substantially greater diameter than the aforesaid tube carried by the rear end of said tube, an inverted receptacle set within the housing and over the rear end of the tube, and means carried by said housing for engaging a mechanism to rotate the assemblage of the said tube and housing.

3. In a coring device of the class described, a tapered tube, said tube tapering toward its forward end, a removable cutting unit engaged by said forward end of the tube, said cutting unit comprising a shank engageable within said tube, a body portion, and a circular cutter carried by said body portion, and a core collecting housing communicating with the rear end of said tube, said housing comprising a main body member of substantially greater diameter than the aforesaid tube and a removable cover member, said cover member having a bushing adapted to engage the drive shaft of a motor.

4. In a coring device of the class described, a tube, and a circular cutter at the forward end of the tube, the internal diameter of the tube

being slightly larger than the internal diameter of the cutter, a core collecting housing of substantially greater diameter than the aforesaid tube carried by the rear end of said tube, and means carried by said housing to engage the 5 drive shaft of a motor.

5. In a coring device of the class described, a forwardly tapering tube, and a circular cutter at the forward end of the tube, the internal diameter of the tube being slightly larger than 10 the internal diameter of the cutter, a core collecting housing of substantially greater diameter than the aforesaid tube carried by the rear end of said tube, and means carried by said housing for engaging a mechanism to rotate the assem- 15 blage of the said tube and housing.

RICHARD T. McANDREW.
